(57) CLAIM

The ornamental design for a beverage bottle, as shown and described.

DESCRIPTION

FIG. 1 is a front view of a beverage bottle, showing my new design.

FIG. 2 is a rear view thereof.

FIG. 3 is a right side view thereof.

FIG. 4 is a left side view thereof.

FIG. 5 is a top view thereof; and,

FIG. 6 is a bottom view thereof.

The broken lines of FIGS. 1-6 illustrate portions of the beverage bottle that form no part of the claimed design.

1 Claim, 5 Drawing Sheets
